Primary Examiner — Richard E Chilcot(74) *Attorney, Agent, or Firm* — Margaret Polson; Polson Intellectual Property Law, PC(57) **CLAIM**

The ornamental design for a body for mobile service robot, as shown and described.

DESCRIPTION

1. Body for a mobile service robot

1.1 : is a front perspective view of my new design for a mobile service robot

1.2 is a front side elevation view of Figure 1.1

1.3 : is a back side elevation view of Figure 1.1

1.4 is a left side elevation view of Figure 1.1

1.5 is a right side elevation view of Figure 1.1

1.6 is a top side plan view of Figure 1.1

1.7 is a bottom side plan view of Figure 1.1

1 Claim, 7 Drawing Sheets(56)
